(57) **CLAIM**

The ornamental design for a combination lobster, crayfish and crab trap, as shown and described.

DESCRIPTION

FIG. 1 is a front elevational view of the combination lobster, crayfish and crab trap showing my new design;

FIG. 2 is a side elevational view thereof from the left of FIG. 1;

FIG. 3 is a side elevational view thereof from the right of FIG. 1;

FIG. 4 is a top plan view thereof;

FIG. 5 is a bottom plan view thereof; and

FIG. 6 is a front elevational view of a second embodiment of the combination lobster, crayfish and crab trap;

FIG. 7 is a side elevational view thereof;

FIG. 8 is an opposite side elevational view thereof;

FIG. 9 is a top plan view thereof; and,

FIG. 10 is a bottom plan view.
